MOVABLE BEARING SUPPORTS FOR PRINTING ROLLS

Stephen B. Stafford, Oxford, and Herman A. Smith, Holden, Mass., assignors to Rice Barton Corporation, a corporation of Massachusetts

Application October 11, 1940, Serial No. 360,786

1 Claim. (Cl. 101—248)

This invention relates to printing machinery and more particularly to the printing roll and its adjustable supports.

A textile printing machine used for printing one or more colors on a fabric usually comprises a printing roll and preferably a series of them so arranged relative to one or more backing cylinders that the fabric may be printed as it passes therebetween. The printing roll comprises a mandrel having removably mounted thereon a hollow copper intaglio roll carrying the impression to be printed on the cloth. The mandrel is usually slightly tapered and the copper roll correspondingly shaped, and the two are assembled with a driving fit. When a given printing run has been completed, the printing roll is removed from the mandrel and the surface thereof is ground down and a new engraving formed thereon. When the roll is again mounted on the mandrel, it may not be located in exactly the same place as it was formerly; hence registration with the fabric to be printed is thus rendered difficult. Moreover, it is necessary that the printing roll be held against the backing cylinder under a high pressure applied at its two ends. This is usually accomplished by means of an adjusting screw. The bearings for the mandrel are customarily made as half bearing blocks to permit ready removability of the roll. If the machine attendant should adjust one end of the mandrel to a position closer to the printing cylinder than is the other end, then this imposes a strain on the bearing and tends to cause trouble. Also, any attempt at adjusting the mandrel lengthwise will lead to difficulty if the bearings are not both adjusted along with the mandrel.

It is the primary object of this invention to overcome these various problems and to provide a printing roll mount so constructed and arranged that the printing roll may be properly adjusted relative to the backing cylinder and moved axially or laterally and wherein the bearings are self-aligning and adjustment of the parts is rendered simple and easily accomplished. Further objects will be apparent in the following disclosure.

Referring to the drawing, which illustrates a preferred embodiment of the printing roll mount:

Fig. 1 is a plan view, partly in section and partly broken away, of a mandrel carrying a bearing roll and supported in two sets of roller bearings, this view being taken substantially on the line 1—1 of Fig. 2; and

Fig. 2 is a fragmentary view, partly broken

away and in section, taken on the line of 2—2 of Fig. 1.

A textile printing machine, which may be the type of the standard Rice-Barton construction, comprises a backing cylinder 10 and a printing roll 12 which are suitably mounted and arranged for printing a cloth or other desired material. The printing roll 12 is preferably provided with a slightly tapering internal cylindrical surface which makes a sliding fit with a steel mandrel 14. This mandrel, on which the printing roll is keyed, is mounted at its two ends in roller bearings. The housings 15 and 16 carrying these roller bearings are in turn mounted on slides to permit proper adjustment of the two ends of the printing roll.

The entire assembly is carried on parallel arms 18 projecting laterally from the frame of the machine. These arms have slideways 19 formed thereon which carry slide blocks 20 and 21. These blocks may be adjusted toward and from the backing cylinder 10 by means of the screws 22 suitably mounted in threaded bushings 23 carried in the arms 18. A pair of rubber buffers 24 are mounted in a recess 25 formed in one end of the bearing blocks 20 and 21, and steel plates 26 serve to transmit the thrust from the screw 21 through these rubber disks to the bearing blocks for forcing the printing roller into engagement with the backing cylinder 10. A collar 27 pinned to the screw 21 serves for withdrawing the block rearwardly, this collar engaging a plate 28 suitably secured by cap screws on the end of the bearing blocks and which is adapted to substantially close the opening carrying the rubber pressure disks. Any suitable construction may however be employed for the purpose of transmitting the pressure to the printing roll.

In order to provide for a lateral adjustment of the slide blocks, a slide 30 is mounted on a block 20 and another slide 31 is mounted on the block 21. Each of the slides is adjusted by means of a construction which comprises a screw 32 or 33 threaded into one of the slides 30 or 31. As shown in Fig. 2, the screw 32 is threaded into the slide 30 and it passes through a projecting flange 34 on the block 20 and carries a collar 35 beneath that flange, the parts being so arranged that rotation of the screw 34 tends to lift the slide 30.

The housings 15 and 16 which carry the roller bearings are provided with partial spherical surfaces 40 and 41, and these surfaces are mounted in similarly shaped recesses 42 and 43 in arcuate shaped bearing blocks. These bearing surfaces 40 and 41 provide rocking supports for the two ends of the mandrel so that the alignment of the

radial bearings and the mandrel is not disturbed if one slide block is moved forward more than is the other. One bearing block is the slide member 31 shown at the left hand side of Fig. 1, while the other arcuate block is a supplemental slide 44. This supplemental slide 44 is adapted to be moved at right angles to the direction of travel of the other slide 30 by means of a screw 46 having a threaded portion passing into the block 44 and having a cylindrical portion passing through a lug 47 on the block 30. Two collars 48 on the screw will serve to locate the screw so that turning movement thereof will move the slide back and forth as required. Each of the slides 30, 31 and 44 is provided with a dovetailed portion interfitting with a similarly shaped dovetailed recess in the supporting member as will be understood.

The arcuate supporting member 44 is shaped as illustrated in Fig. 2 to provide a half bearing support for the roller bearing housings 16. The other member 31 is similarly shaped to provide a half bearing support for the other housing 15. These members 31 and 44 extend in an arc less than 180°, so that the roller bearing housings may be removably placed in position, and each half bearing support projects under the bottom of the housing in the manner shown in Fig. 2, so that the housing will be properly supported when the printing roll is not bearing against the backing cylinder 10. The construction is such that if the operator adjusts one of the pressure screws 22 more tightly than the other, the bearing housings 15 and 16 will merely rock in their spherical bearing supports and thus the bearing housings will properly align with the associated parts without imposing any strain on the mandrel or the bearing block.

An important feature of this invention resides in having one of the bearing housings so constructed as to provide only a radial support for the mandrel, while the other provides both a radial support and a thrust bearing, so that the printing roll may be moved endwise simply by movement of this particular bearing. To that end the left hand bearing, which is only a radial bearing, comprises the housing 15 shaped to carry two roller bearing rings 50 therein. Each has an inwardly turned flange 52 which serves to hold the rollers 53 and their associated rings 54 and 55 in position. A spacing ring 56 is located between the supporting rings 50 and thus holds them properly located between the flange 57 on the housing and an adjusting plate 59 which is threaded into the housing 15. The sleeve 58 which forms the inner ring for each of the sets of roller bearings is fitted on the end of the mandrel and slides through the bearing housing when the mandrel moves endwise. It will thus be seen that the left hand bearing provides only for a radial support for the mandrel.

The right hand bearing is similarly constructed except that it comprises a radial rib 60 formed on the inner raceway member 61 which is fitted on the mandrel. A pair of rollers 62 carried in suitable supporting rings 63 are mounted to contact with the sides of this radial rib 60. They also bear against the inwardly turned flanges 66 of the radial thrust raceways 67. The radial rollers 68 are mounted the same as are the rollers 53 above described, and the parts are held in position by the ring 70 threaded into the housing 16. The spacing ring 71 locates the bearing raceways 67 and provides for a proper fit of the parts within the housing.

The inner raceway sleeves 58 and 61 are each held in position against an inner shoulder 72 on the mandrel by means of clamping devices comprising two semi-cylindrical members 74 hinged to similarly shaped parts 75 and arranged to be held in position by means of clamping bolts 76 passing through lugs projecting laterally therefrom, as will be readily understood. Each of these clamping rings fits tightly against the outer ends of the inner raceways 58 or 61 and against a beveled shoulder 78 formed on the mandrel. Hence, by drawing the two clamping rings tightly together by means of the screw threaded bolt 76, the parts are forced into a tight assembly on the mandrel.

The operation of these various parts will be readily understood in view of the above description. The printing roll 12 is removably fitted onto the central portion of the mandrel. The bearing housings 15 and 16 with their inner bearing raceways 58 and 61 are slidably mounted on the ends of the mandrel and the locating rings formed of parts 74 and 75 are put into place to hold the bearings firmly in position. The assembled parts are then ready to be dropped into position in the half bearing blocks formed by the parts 31 and 44 which have the partial spherical surfaces 41 and 48 arranged to provide rocking supports for the bearing housings. Then the various slides are adjusted to move the printing roll into suitable contact with the backing cylinder by adjustment of the pressure screws 22. If the operator should adjust one pressure screw a little more tightly than the other, this will not disturb the alignment of the radial bearings with the mandrel, since the bearing housings may rock freely on the partial spherical rocking bearing surfaces 42 and 43. If the printing roll 12 has been put on the mandrel in a slightly different position from that which it formerly occupied, then the machine operator may move the printing roll lengthwise or axially together with its mandrel by turning the screw 46 and moving the slide 44. This movement is transmitted through the thrust bearings and the radial flange 60 of the right hand bearing housing assembly and thereby serves to move the printing roll and cause the inner raceway ring 58 to slide lengthwise through the left hand bearing housing 15 without disturbing either of the bearing assemblies. Also, any suitable adjustment of the screws 32 may be employed to raise or lower the printing roll relative to the backing cylinder as may be required. It will, therefore, be seen that we have provided a self-aligning bearing assembly for supporting the printing roll which permits adjustments axially and radially of the printing roll without disturbing the alignment of the bearings. It will now be appreciated that various arrangements may be made in the relative positions of the slides and the associated bearing supporting parts and that numerous modifications may be made of this construction within the scope of this invention. Hence, the above description is to be interpreted as illustrative of the general principles of the invention and not as limitations on the claim appended hereto.

I claim:

A textile printing machine comprising a frame, a rotatable backing cylinder and a printing roll associated for a printing operation, a rotatable mandrel removably carrying the roll, a pair of spaced slide blocks which are separately adjustable toward and from the cylinder, a bearing

housing carried by each slide block, means providing a universal bearing for supporting each housing on an associated slide block, a radial bearing in one housing carrying one end of the mandrel and permitting axial movement thereof, radial and end thrust bearings in the second housing for carrying the other end of the mandrel and preventing relative axial movement thereof, and means carried by one of said slide

blocks for moving said second housing and its bearings axially and adjusting the mandrel endwise through the bearings of the first housing, said universal bearings serving to align the housings and their bearings with the mandrel for all normal adjustments of said devices.
